UNITED STATES PATENT OFFICE.

ALONZO EVERETT DARBY, OF LAKESIDE, WASHINGTON.

SLING FOR CONTAINERS.

Application filed April 26, 1922. Serial No. 556,757.

To all whom it may concern:

Be it known that I, ALONZO EVERETT DARBY, a citizen of the United States of America, and a resident of Lakeside, in the county of Chelan and State of Washington, have invented a new and Improved Sling for Containers, of which the following is a description.

10 My invention relates to a sling more particularly adapted for fruit containers to hold the container while it is being filled and thereby saving one handling of the fruit which now is picked into a bucket or bag and then poured into a container.

15 The general object of the invention is to provide a novel sling for the indicated purpose, whereby the container may be securely held in supported position in the sling or released with facility.

20 The nature of the invention and its distinguishing features and advantages will clearly appear as the description proceeds.

Reference is to be had to the accompanying drawings forming a part of this specification, it being understood that the drawings are merely illustrative of practical examples of the invention.

Figure 1 is a perspective view of a sling embodying my invention;

30 Figure 2 is a plan view thereof with the container in position;

Figure 3 is a longitudinal vertical section on the line 3—3, Figure 2; showing the parts in position with the container-engaging elements in the inner position;

35 Figure 4 is a vertical section similar to Figure 3 with the engaging elements in the outer position;

Figure 5 is a transverse vertical section as indicated by the line 5—5, Figure 3;

Figure 6 is a fragmentary perspective view showing a slight modification in the swingable container-engaging elements;

Figure 7 is a view similar to Figure 6 but showing a further slight modification.

In carrying out my invention in the form shown in Figures 1 to 5, a skeleton sling body 10 is used which for lightness is formed of wire and presents rectangular top and bottom frames connected by corner posts 10^a. Shoulder straps 12 are provided secured at the front to hanger loops 11 provided on the rear longitudinal member of the top frame near the ends of said longitudinal member. Said loops 11 are integral in practice with vertical tie

wires 11^a extending between the top and bottom frames. At the back said straps converge and are secured to an arched member 13 projecting above the front longitudinal member of the top frame. Said arch member 13 is here shown as integral with tie wires 13^a, extending between the top and bottom frames of the body at the front, the material forming said arch and tie wires being given turns as at 14 about the front longitudinal bar of the top frame.

Engaging elements 15 are provided at the bottom of the body 10 at each end to engage beneath a container A, said elements in the form shown in Figures 1 to 5 having rectangular depressed portions 16 to accommodate the bottom cleats in the container A.

75 In Figure 6 is shown the engaging elements 15^a adapted to be disposed beneath the bottom of a container formed without the cleats. In Figure 7 the engaging elements 15^b are the same as the elements 15 except that they have rounded outer corners 15^c to conform to a container having rounded corners.

70 The elements 15 at each end of the body 10 are integral with levers 18, the material forming the levers and engaging elements being given a turn at each side arm thereof as at 17 about the bottom frame of the body to swing on the body to a position for carrying the engaging elements 15 beneath the container A or to swing said elements laterally outward away from the planes of the ends of the container.

75 The material forming a lever 18 at the upper end thereof is formed with a depressed portion 19 which extends through a link 20 which presents a longitudinal slot 21 in which the lever at its upper end may have sliding and rockable movement. At the lower end of the slot 21 the link 20 curves laterally outward so that the depressed portion 19 of the lever will so engage the link 20 as to prevent swinging movement of the lever, whereby to maintain the engaging elements 15 beneath the container A. At the upper end of the slot 21 a bend is formed in the link 20 to provide a shoulder 23 to engage the depressed portion 19 of lever 18 in a manner to hold the engaging elements 15 in the outer position away from the plane of the container as shown in Figure 4.

The link 20 is hung at its upper end on a suitable member of the body 10. As here shown said link 20 has the upper ends of its side arms formed with eyes 20^a through 5 which passes a horizontal end bar 24 slightly below the top of the body 10. Each bar 24 has its ends secured as by eyes 25 to the adjacent end member of the top frame of the body 10, the bar 24 being braced by a vertical tie wire 26 connecting said bar with the end member of the bottom frame. The upper ends of the levers 18 serve as finger holds for operating the lever for throwing the engaging elements 15 to the inner or outer positions. It will be observed that the upper end of the link 20 is on a fixed member of the frame 24 and the lever 18 fulcrumed on the fixed member of the bottom so that simple and direct movements of the lever serve 15 to throw the engaging elements 15 to either position and it will be further noted that the lever 18 and link 20 are automatically locked against movement in both positions of the engaging elements, 15.

25 I would state in conclusion that while the illustrated examples constitute practical embodiments of my invention, I do not limit myself strictly to the exact details herein illustrated, since, manifestly, the same can 30 be considerably varied without departure from the spirit of the invention as defined in the appended claims.

Having thus described my invention, I claim:

35 1. A sling for containers including a body, elements swingingly mounted on the body at the bottom for movement beneath a container or laterally outward from the engaging position, a lever to actuate said retaining elements, and a link pivoted at its

upper end on the body and having sliding and rocking engagement with said lever, said lever at its upper end and said link at the upper and lower ends of the slot having 45 co-engaging members to automatically hold the lever in position with said engaging elements in either the inner or the outer position.

2. A sling of the class described including a body adapted to receive a container, engaging elements for the container, mounted on said body at the bottom to swing beneath the container or outwardly away from the container, levers having connection with 50 said elements to swing the same to either position, and links pivoted to the frame at their upper ends and formed with longitudinal slots through which members of the levers at the upper ends of the latter pass, 55 said links having their lower ends curved laterally outward and formed with shoulders near the upper ends of the slots, said lower ends and said shoulders adapted to engage the said members of the levers to hold 60 the levers with said engaging elements in either position.

3. A sling of the class described including a body adapted to receive a container, engaging elements for the container mounted 70 on said body at the bottom to swing beneath the container or outwardly away from the container, levers having connection with said elements to swing the same to either position, and links pivoted to the frame at 75 their upper ends, said links having means to automatically effect holding engagement with the lever and prevent accidental movement thereof in either position of said container-engaging elements.

ALONZO EVERETT DARBY.
